KNICKKNACK SHELF

Noah Rubin, New York, N. Y., assignor to National Plastic Corp., New York, N. Y., a corporation of New York

Application October 29, 1949, Serial No. 5,773

Term of patent 3½ years

(Cl. D33—3)

To all whom it may concern:

Be it known that I, Noah Rubin, a citizen of the United States, residing in New York city, county and State of New York, have invented a new, original, and ornamental Design for Knick-Knack Shelf, of which the following is a specification, reference being had to the accompanying drawing, forming a part thereof, in which:

Fig. 1 is a front elevational view of a knick-knack shelf showing my new design, the left hand portion shown in broken lines being similar to the right hand portion shown in full lines, and

Fig. 2 is a top plan view thereof.

I claim:

The ornamental design for a knick-knack shelf, as shown and described.

NOAH RUBIN.
